Primary Examiner — Shannon Morgan

(57) **CLAIM**

The ornamental design for a container for liquids, as shown and described.

DESCRIPTION

FIG. 1 is a perspective view of a container for liquids showing our new design;

FIG. 2 is a bottom perspective view of the container for liquids thereof;

FIG. 3 is a side view of the container for liquids thereof;

FIG. 4 is a rear view of the container for liquids thereof;

FIG. 5 is a front view of the container for liquids thereof;

FIG. 6 is a top plan view of the container for liquids thereof; and,

FIG. 7 is a bottom plan view of the container for liquids thereof.

The broken lines in FIG. 2 depict portions of the container for liquids that form no part of the claimed design.

1 Claim, 6 Drawing Sheets
